UNITED STATES PATENT OFFICE.

HENRY PRICE BALL, OF PITTSFIELD, MASSACHUSETTS, ASSIGNOR TO GENERAL ELECTRIC COMPANY, A CORPORATION OF NEW YORK.

ELECTRIC HEATING UNIT.

1,096,820.

Specification of Letters Patent.

Patented May 19, 1914.

Application filed December 21, 1912. Serial No. 737,966.

To all whom it may concern:

Be it known that I, HENRY PRICE BALL, a citizen of the United States, residing at Pittsfield, in the county of Berkshire, State 5 of Massachusetts, have invented certain new and useful Improvements in Electric Heating Units, of which the following is a specification.

My invention relates to electric resistance 10 heating units, and more particularly to units of that character which are made with a substantially flat heating surface, and are suitable for various uses either independently or in connection with other apparatus.

Electric resistance heating units of this 15 character ordinarily comprise an electric resistance element inclosed by electric insulation and an outer casing of metal. The electric insulation must be such as to prevent 20 leakage of current and short circuits and must also be such that there will be a low thermal drop between the resistance element and the casing. It is customary to use electric insulations such as mica which have a 25 high dielectric strength and comparatively low thermal resistance. A comparatively thin body of such insulation is ordinarily sufficient to guard against electric leakage and short circuits. It is desirable, however, 30 that such insulation be firmly compressed between the resistance element and the metal casing of the unit in order that air which has a comparatively high thermal resistance 35 be eliminated as much as possible and that the inclosed parts be held firmly in place.

My invention has for its object the production of a compact and rugged heating unit of the above described character in 40 which the insulation is firmly compacted between the casing and the resistance element and will remain in this condition indefinitely.

My invention comprises an improved heating unit of the aforesaid character and the 45 method of making the same.

In carrying out the method constituting part of my invention I inclose the resistance element and insulation in a casing formed of two metal plates. In accomplishing this 50 I first form a recess in one of the plates of substantially the shape and size as the resistance element and insulation by applying pressure thereto. In forming the aforesaid recess a portion of the plate of substantially 55 the same dimensions as the recess is dis-

placed from the plate. The resistance element and insulation are then inserted in the recess and the plates are permanently fastened together. The structure thus formed is then subjected to considerable pressure so that the displaced portion of the casing is forced partially back to its original position. The metal of which the casing plates are composed should be such that it will accommodate itself readily to the aforesaid operations and it should therefore be fairly malleable. Iron or comparatively soft steel are quite suitable for this purpose.

Although the recess in the casing plate may be formed in such a way that it is more or less cup-shaped, I prefer to form such recess by partially or completely shearing the plate. This has the advantage over cupping the plate that in the subsequent compression of the unit there will be a more direct application of the compression forces to the parts in the casing and less distortion of the casing. The reason for this is that when the shearing operation is utilized the sides of the recess and of the displaced 60 or projecting portion of the plate are straight, perpendicular to the face of the plate and in line with each other. In case the cupping operation is utilized, the sides of the recess and of the displaced portion 65 are more or less curved thus departing from a direction perpendicular to the plate, and are obviously not in line with each other. In case the plate has been previously sheared, the final compression acts only to force the 70 displaced portion against the inclosed parts 75 of the unit, without distorting the plates of the casing. The compressing force is therefore utilized completely in compacting the 80 unit. On the other hand, if the plate has 85 been cupped, the compression force resolves itself into two components one of which is 90 normal to the plate and does useful work in compressing the unit and the other parallel with the plate which does no useful 95 work but on the contrary distorts the plate 100 by causing a lateral flow of the metal. As the compressing proceeds, the accumulation of metal due to the buckling of the sides of the displaced portion of the plate causes a 105 large part of the compressing force to be wasted in flattening said metal thus diminishing the actual compression on the inclosed parts. Moreover such accumulation detracts from the appearance of the plate.

In the preferred form of my invention I may either partially or completely shear the plate in forming the desired recess. I prefer to partially shear because the un-sheared portion assists in holding the sheared portion in place. However, I may completely shear and in such case the friction of the punched out portion against the walls of the recess serve to hold it in place after the final compression of the unit.

10 My invention will be more clearly understood by referring to the accompanying drawing in which—

15 Figures 1 and 4 inclusive illustrate in vertical section the method constituting part of my invention; Figs. 5 and 6 illustrate a modification of the same; Fig. 7 is a plan view of a heating unit embodying my invention and Fig. 8 is a vertical section of the 20 same.

25 Referring to the drawing and particularly to Figs. 1 to 4 inclusive, 10 is the plunger of a hydraulic or other press, 11 is a die co-acting with the same and having an annular recess 12 formed in the upper surface thereof. The said recess is rectangular in vertical cross-section. The lower surface of the plunger 10 is shaped to fit into the recess 12 of the die 11 and for this purpose is provided 30 with a circular recess 13 rectangular in cross-section and located at the center of the plunger. The plate 14 of iron or steel is placed in position over the die and the plunger 10 is forced against the same where- 35 upon the parts assume the positions shown in Fig. 2. The portion 15 is displaced from the plate 14 due to the partial shearing of the said plate. An annular recess 16 is thus formed in the said plate, the sides of which 40 are in line with the sides of the displaced portion 15. In Fig. 3 is shown the plate 14 after the punching operation, the insulation 17, the resistance element 18 and the cover plate 19, the latter being formed of the same 45 material and preferably of the same dimensions as the plate 14. After the parts have been assembled, they may be secured together as by riveting as shown in Fig. 7 at 20 so as to hold them firmly in position. 50 The next step is to permanently unite the two plates and this may be done by welding. I prefer to spot-weld the plates at the center and at a number of points around the edges on account of the fact that when 55 united in this way there will be no warping such as would arise from a continuous weld due to the high temperature. The structure thus formed is then placed in the hydraulic or other press, as shown in Fig. 41 and submitted to a considerable pressure. This results 60 in the displaced portion 15 being firmly compressed against the resistance element and insulation to force the same tightly against the plate 19.

65 In Figs. 5 and 6 is illustrated a modifica-

tion of the above described method. This consists in completely shearing the plate 14 instead of partially shearing the same. The remaining steps of the method are substantially the same as those in the other species of my invention hereinbefore described. As shown in Fig. 6 the punched out portion 15 has been partially forced back to the original position and is held in position by the friction between the same and the sides 75 of the recess 16.

In Figs. 7 and 8 is illustrated the complete unit made by the first of the above described methods. The same comprises the casing 14, 19 with the inclosed resistance element 80 and insulation held firmly in position by the displaced portion 15 of the plate 14. Suitable terminals 21 may be provided. These are attached to loops 22 projecting from the resistance element 18. Insulating 85 bushings 23 surrounding said terminals are held in place by metal sleeves 24.

Owing to the fact that the portion displaced by the punching operation is partially forced back to its original position, 90 the insulation is firmly compressed between the resistance element and the parts of the casing and air spaces with their comparatively high thermal resistance are eliminated. By reason of the fact that the recess 95 in at least one of the plates is formed by the shearing operation, in the subsequent compression of the unit the force is applied in a direction such that it will not be fully applied to the inclosed parts of the unit and 100 will not distort the plates by causing them to buckle.

Various modifications of the above described method and article will readily suggest themselves to those skilled in the art 105 and are to be considered as coming within the scope of my invention which is set forth in the following claims.

What I claim as new and desire to secure by Letters Patent of the United States is:— 110

1. The method of making an electric resistance unit which consists in displacing a portion of the metal plate to form a recess therein by applying pressure to the plate, placing a resistance element and insulation 115 in said recess, placing a cover plate over said recess and compressing the structure thus formed to force the part of the plate displaced by the pressing operation partially back to its original position. 120

2. The method of making an electric resistance unit which consists in displacing a portion of the metal plate to form a recess therein by shearing the plate, placing a resistance element and insulation in said recess, placing a cover over said recess and compressing the structure thus formed to force the part of the plate displaced by the shearing operation partially back to its 125 original position. 130

3. The method of making an electric resistance heating unit which consists in punching a recess in a metallic plate, inserting therein an electric resistance element and insulation, placing another metallic plate over the said recess, uniting the said plates and then compressing the structure thus formed to force the punched portion into close thermal contact with the inclosed parts.
4. The method of making an electric resistance heating unit which consists in shearing a metallic plate to form a recess therein, placing an electric resistance element and insulation in said recess, uniting a cover plate to the aforesaid plate and then forcing the portion displaced by the shearing operation firmly against the insulation and heating element.
5. An electric heating unit comprising a pair of metallic plates, one of which is provided with an offset portion forming a recess, and an insulated resistance element within the said recess and compressed between the offset portion and the other plate.
6. An electric heating unit comprising a pair of contacting metallic plates one of which is provided with a recess formed by displacing a portion thereof parallel with the plate, and a resistance element within said recess and compressed between the displaced portion and the other plate.
7. An electric heating unit comprising a metallic plate provided with an annular recess formed by displacing an annular portion parallel with the plate, a cover plate, and a resistance element within said recess and compressed between the displaced portion and the other plate.
8. An electric resistance heating unit comprising a pair of contacting metallic plates, one of which is provided with an offset annular portion forming on one side an annular recess and on the other side an annular displaced portion, the walls of which are substantially in line with those of the recess, and an insulated resistance unit located in said recess, the two plates being secured together at a plurality of points.

In witness whereof, I have hereunto set my hand this 17th day of December, 1912.

HENRY PRICE BALL.
